UNITED STATES PATENT OFFICE.

LOUIS S. REYNAL, OF NEW BRITAIN, CONNECTICUT, ASSIGNOR TO THE AMERICAN PAPER GOODS COMPANY, OF KENSINGTON, CONNECTICUT, A CORPORATION OF NEW JERSEY.

METHOD OF MAKING PAPER DRINKING-CUPS.

1,254,850.

Specification of Letters Patent. Patented Jan. 29, 1918.

Application filed January 15, 1917. Serial No. 142,389.

To all whom it may concern:

Be it known that I, LOUIS S. REYNAL, a citizen of the United States, residing at New Britain, in the county of Hartford and State 5 of Connecticut, have invented certain new and useful Improvements in Methods of Making Paper Drinking-Cups, of which the following is a specification.

This invention relates to a method of 10 making paper drinking cups. One of the fundamental purposes of the method is the production of cups in an economical manner, which is an important consideration. The initial step in the preferred form of the 15 method consists in cutting in any desirable manner from a sheet of suitable paper stock, blanks from which the necessary cups are to be formed, the cuts being on successively opposite angles, the result being that there is 20 virtually no stock wasted; as a matter of fact there is practically no stock lost after the first angular cut is made and until the last angular cut is finished. Each blank as will be clear, has side edges which converge 25 in one direction and diverge in the opposite along practically similar angles, owing to which circumstance when a blank is cut, the cut defines the inner side edge of the severed blank and the outer side edge of the 30 blank to be next cut.

While a cup can advantageously be made from this type of blank, it is conceivable that it could be made from some other style of blank. A cup made by the method possesses 35 a desirable amount of strength, and is sufficiently reinforced as to prevent its accidental leakage while in use under ordinary conditions. The cup is of such nature that it can be easily opened.

40 In the drawings accompanying and forming part of the present specification I have shown certain ways of carrying the method into effect. These I will set forth in detail in the following description. Obviously I 45 do not restrict myself to this particular construction; I may depart therefrom in several respects within the scope of the invention defined by the claims following said description.

50 Referring to said drawings:

Figure 1 is a developed view of a sheet showing how cup blanks can be cut therefrom, one of the blanks being completely severed from the sheet.

Fig. 2 is a view of several of the blanks 55 arranged side by side.

Fig. 3 is a view of one of the blanks, the dotted lines showing the transverse fold lines.

Fig. 4 is a similar view, the longitudinal 60 and transverse fold lines also appearing and additional dotted lines showing the outer or lateral folds.

Fig. 5 is a view of the blank doubled on itself to present the leaves of the cup, the 65 dotted lines showing the lateral folds and also the longitudinal fold.

Fig. 6 is a view in elevation of the finished cup.

Fig. 7 is a perspective view of the cup 70 opened.

Like characters refer to like parts throughout the several views.

As I have already observed one important feature in connection with the method is the 75 fact that I can use stock in web or flat form from which can be cut by suitable means, the cup blanks with practically no waste. In Fig. 1 I have shown such a sheet or web 80 2. As illustrated the side edges of the sheet are straight and in parallelism, which is the preferred relation, although not always necessary. This sheet is or may be of the material usually employed in making paper drinking cups. It is alternately cut along 85 opposite angles as 3, 4, 5 and so on. The web or stock 2 is generally in the form of a roll and the web of paper or equivalent material may be advanced and cut in a machine or even by hand to produce the requisite blanks one as 6 of which is shown in said Fig. 1 as wholly severed from the sheet. In Fig. 2 I have shown several of such blanks 6 arranged side by side. The side edges of 90 the cup blank 6 it will be seen, converge on equal angles toward one end of the sheet and naturally diverge toward the other. It will be apparent that when the web or sheet 2 is cut up to form the cup blanks as 6, no particle goes to waste unless I except the two 100 small triangular pieces at the ends of the web, and they are of practically no consequence. When a blank as 6 is cut away from the sheet 2, the line of severance between it and the front edge of the sheet defines one 105 edge of the cut blank and the opposite edge of the blank next to be cut and so on.

After a blank as 6, which is merely one

of several, is obtained, it is longitudinally creased or scored as at 7 from one end to the other as a matter of preference, although not of absolute necessity. This longitudinal creasing of the blank facilitates the opening of the finished cup as best illustrated in Fig. 7. After the blank is scored or creased in the manner to which I have just alluded, it is folded or doubled on itself along the transverse fold line 8 to produce the leaves 9 and 10 which are superimposed upon each other, the two leaves constituting sides of the cup. These are shown in their superimposed relation in Fig. 5. The leaf or side 10 as shown is a trifle longer than the complemental wing or side 9, the result being that the upper portion of the former extends upwardly beyond the upper edge of the latter, the extending portion of the leaf 10 constituting a finger or thumb piece which can be grasped to facilitate the opening of the finished cup. There may be cases where I can dispense with the longitudinal crease or fold 7 and rely upon the extension of the leaf 10 to open the cup or vice versa but by providing for both conditions I insure the opening of the cup in a highly satisfactory manner. I desire to call attention to the fact that the transverse fold lines 8 of alternate blanks are situated respectively at opposite sides of the longitudinal central line or axis 11 of the web or sheet 2; this is indicated in Fig. 2. It will be noted that when the blank 6 has been folded or doubled on itself transversely to produce the complemental leaves, the leaf 9 is wider than the leaf 10. As a consequence I will consider the former the wide leaf and the latter the narrow leaf.

After the blank has been doubled or folded on itself transversely to produce the said two leaves, the folded blank is laterally folded upon itself on opposite sides along the lines 12 and 13, these fold lines best appearing in Fig. 4 and extending longitudinally of the two leaves. By folding the blank laterally on itself I produce side flaps 14 on the wide leaf 9 and side flaps 15 on the leaf 10. The two series of fold lines 12 and 13 converge inwardly toward the transverse fold which it will be noted constitutes the bottom of the cup the respective lateral fold lines which produce these side flaps meeting said transverse fold lines. These transverse folds which produce the flaps or tabs extend the complete length of the wide leaf 9 but only part of the length of the narrow leaf, the fold lines commencing with the transverse fold and continuing to about a half or a trifle more than a half the height of the cup. This is fully illustrated in Fig. 5. After the fold lines 12 and 13 have been made to secure the side flaps or wings 14 and 15 a suitable adhesive as 16 is applied to these side wings.

While generally speaking this adhesive may be applied at any suitable time, it is usually put on after the transverse fold 8 is made. It will be seen that with the blank transversely folded and with the lateral fold lines present, the wings 15 cross the lower ends of the wings 14. The adhesive 16 is applied to the said side wings or flaps 14 and 15 near their outer edges as shown in said Fig. 5, the adhesive areas being of such width, however, that when the cup is finished, the adhesive will not come against the inner surface of the wide leaf 9 but will attach itself only to the narrow leaf 10 as otherwise opening of the cup would be prevented. After the adhesive is applied, the side wings will be folded over onto the narrow leaf 10, and when the adhesive is set, the cup will be finished and in readiness for use.

It will, of course, be clear that the narrow leaf of the cup has a side flap or wing as 15 folded on and adhering to itself and that the wider leaf has side wings folded on itself and superimposed on the outer surface of the narrow leaf. The wings of the two side pairs are as shown integral with each other, the result being that when the cup is finished, it will be effectually closed against accidental leakage under ordinary conditions for a considerable distance, as already observed, slightly more than a half from its lower or closed end. It will also be noted that the sides of the cup converge toward the closed end thereof. The important fact to which I wish to call attention is that the lateral wings converge toward the closed end of the cup, extending the complete length of the wide leaf 9 for a part of the length of the narrow leaf 10 and what is most important that their inner edges are continued approximately to the upper edge of the narrow leaf to which it will be remembered they are adhesively united. This last mentioned relation is shown clearly in both Figs. 6 and 7.

It will be remembered that I have referred to the fact that the blank 6 when flat is longitudinally centrally creased at 7. It will be understood that when the blank is doubled on itself to form the companion leaves 9 and 10, this crease will be formed practically equally in the two leaves but the portions of the crease will be opposite, the result being that when the cup is pressed inward from opposite sides of the crease its opening is appreciably facilitated without the necessity of having recourse to the projecting portion or tongue of the longer leaf 10.

If the sheet be of waterproof material it is not necessary that the blanks or finished cups should be water proofed. If the opposite be the case waterproofing substance such as paraffin can be applied to the paper or

equivalent material at any suitable stage in the method.

What I claim is:

1. A method of making drinking cups which comprises cutting from a sheet in web form a succession of blanks along oppositely inclined angles, so that each cut will form the side of one blank and the side of a succeeding blank, then transversely folding the blanks on lines alternately at opposite sides of the longitudinal center line of the sheet and finally closing against liquid leakage the sides of the transversely folded blanks to form drinking cups.
2. A method of making drinking cups which comprises cutting from a sheet in web form a succession of blanks along oppositely inclined angles, so that each cut will form the side of one blank and the side of a succeeding blank, then transversely folding the blanks on lines alternately at opposite sides of the longitudinal center line of the sheet, and finally in closing with an adhesive the sides of the transversely folded blanks to form drinking cups.
3. A method of making drinking cups which comprises cutting from a sheet in web form a succession of blanks along opposite angles so that each cut will form sides of immediately succeeding blanks, longitudinally centrally scoring the blanks, transversely folding the same along lines located alternately at opposite sides of the longitudinal central line of the sheet, and finally closing against liquid leakage, the sides of the transversely folded blanks to form drinking cups.
4. A method of making a drinking cup from a blank having converging side edges, which comprises folding the blank on itself along a straight line at one side of the transverse center line of the blank to produce two leaves of different lengths, the side edges of the longer leaf thus converging toward the open end of the folded blank, and the side edges of the shorter leaf diverging toward said open end, then applying an adhesive to both leaves near their side edges, for the entire length of the short leaf, then folding the lateral portions of both leaves on themselves along lines which diverge toward the open end of the blank to cause the parts of the blank which have the adhesive to adhere only to the outer surface of the long leaf.
5. A method of making a drinking cup from a blank, having converging side edges, which comprises folding the blank on itself along a longitudinal median line, folding the blank on itself along a straight line at one side of the transverse center line of the blank to produce two leaves of different lengths, the side edges of the longer leaf thus converging toward the open end of the folded blank and the side edges of the shorter leaf diverging toward said open end, then applying an adhesive to the leaves near their side edges for approximately the entire length of the leaves, then folding the lateral portions of both leaves on themselves along lines which diverge toward the open end of the blank to cause parts of the blank which have the adhesive to adhere only to the outer surface of the long leaf.
6. A method of making a drinking cup from a blank having converging side edges, which comprises folding the blank on itself along a straight line extending transversely of the blank to thus produce two leaves, the side edges of one of the leaves converging toward the open end of the folded blank and the side edges of the other leaf diverging toward said open end, then applying an adhesive to the leaves near their side edges for approximately the entire length of the folded blank, then folding the lateral portions of both leaves on themselves along lines which diverge toward the open end of the blank to thus cause the laterally folded portions of the blank provided with the adhesive to adhere only to the outer surface of that part of said leaf the side edges of which converge toward the open end of the cup.
7. A method of making a drinking cup from a blank having converging side edges, which comprises folding the blank on itself along a straight line extending transversely of the blank to produce two leaves, the side edges of one of the leaves converging toward the open end of the blank and the side edges of the other leaf diverging toward said open end, then applying an adhesive to the leaves near their side edges for approximately the entire length of the leaves, then folding the lateral portions of both leaves on themselves on lines which diverge toward the open end of the blank and which cross the lateral portions of the leaf the side edges of which converge toward the open end of the blank for a distance greater than half the length thereof from the transverse fold line, to cause parts of the blank which have the adhesive to adhere only to the outer surface of the blank the side edges of which converge toward the said open end.
8. A method of making a drinking cup from a blank having converging side edges, which comprises longitudinally scoring the blank, transversely folding the same to produce superimposed leaves, and then closing the lateral portions of the leaves to produce a drinking cup.

In testimony whereof I affix my signature in the presence of two witnesses.

LOUIS S. REYNAL.
